ENVELOPE FLAP MOISTENING DEVICE

Frederick W. Storck, Arlington, Mass., assignor to
 Standard Mailing Machines Company, Everett,
 Mass., a corporation of Massachusetts

Application August 28, 1936, Serial No. 98,316

17 Claims. (Cl. 91—43)

My invention relates to improvements in devices for moistening the gummed areas of flaps of envelopes and is particularly adapted to mailing machines of an optional envelope sealing 5 and non-sealing character.

In the usual type of mailing machine, the envelopes to be operated upon are deposited in a hopper or magazine in stacked formation and stripped singly therefrom. Mailing machines of 10 the referred to character are adapted to perform various combinations of mail handling operations; for example, seal the envelope flap and print indicia thereon, print indicia thereon without sealing the envelope flap. When the envelope flaps are to be sealed, the stripped envelope 15 is conveyed, by suitable means, to the moistening device where the envelope flap is engaged and the gummed area moistened.

Since the disclosure, as contained in my 20 United States Letters Patent No. 1,609,218, which eliminates the requirements and disadvantages of bibulous materials commonly used in this type of moistening, it is known that by providing a moistening device with a narrow, elongated capillary slot, or capillary openings, adapted to 25 be sealed by the surface tension of the fluid, and an air-locked fluid supply; when the gummed area of the envelope flap is wiped across the slot, due to the affinity of the gummed area for water, sufficient fluid is drawn from the slot to moisten 30 only this area for subsequent sealing of the flap to the envelope body.

Mailing machines, in general use, are adaptable to envelopes of various sizes and characters. 35 Envelopes are manufactured in various sizes and their flaps have various contours and gummed areas, therefore, a characteristic in particular that is required of a moistening device embodied with a mail handling machine is that the machine and moistening device must be readily 40 adaptable to properly handle and engage these various gummed areas of the flaps with the moistening device prior to being sealed. This requires that these envelope flaps, of various 45 contours, must be separated and positioned from the envelope body prior to engagement with the moistening fluid.

A disadvantage commonly experienced in mail 50 handling machines is that, when the envelope is advanced by the feed rollers, the folded edge of the envelope flap will become displaced, that is, the feed rollers will move the flap out of its normal folded position and cause another folding line between the envelope flap and the envelope

body and when thus sealed, the piece of mail matter presents an unsightly appearance.

Accordingly, the principal object of my present invention is to provide a novel and efficient envelope moistener of a simple construction 5 which will, without adjustment relative to the flap contour, automatically separate envelope flaps of any shape from the envelope body and moisten the gummed area thereof, preparatory to the sealing of the flap to the envelope body. 10

Another object in my invention is to provide a novel and simple device whereby the envelope and flap may be guided in either an engaging or non-engaging relation relative to the moistener so that the mailing machine, with which my device is associated, may be optionally used to seal 15 the envelope flaps or not seal or even open the flaps of the envelopes.

Another object in my invention is to provide a novel construction and arrangement of feed 20 rollers whereby the envelope is advanced without displacing the folded edge of the envelope body and flap.

A further object in my present invention is to provide a novel adjustable means wherein the 25 advancing edge of the envelope body and flap are positively separated from one another and to assure engagement of the flap with the moistener.

A still further object is to provide a novel, 30 sectionally yieldable element to insure contact of the envelope flap with the moistening aperture as the flap is advanced in its line of travel.

Another object is to provide a simple air-locked fluid reservoir that may be replenished 35 with fluid without removing the reservoir, thereby eliminating the possibility of spilling the contents of the reservoir during replenishment.

With the above and other objects in view, my 40 invention comprises a novel combination and arrangement of parts hereinafter described and more specifically pointed out in the appended claims.

In the accompanying drawings I have shown 45 my invention sufficient to enable those skilled in the art to understand the construction and operation thereof.

Referring to the drawings:

Fig. 1 is a transverse section of my moistening device attached to a portion of a mailing machine. 50

Fig. 2 is a plan view of my moistening device, as illustrated at Fig. 1, viewing in the direction of arrow *a*, same figure; in this view the supply reservoir is omitted. 55

Fig. 3 is a sectional view taken substantially along line 3—3, Fig. 1 and viewing in the direction of arrow *b*, same figure.

Fig. 4 is a view corresponding substantially to Fig. 3, but shows some of the parts in a different position.

Fig. 6 is a sectional view taken substantially along line 6—6, Fig. 3.

Fig. 7 is a sectional view taken substantially along line 7—7, Fig. 4.

Fig. 8 is a detached sectional elevation of my yielding contact elements.

Fig. 9 is a view corresponding substantially to Fig. 8, but shows some of the parts in a different position.

Fig. 10 is a section taken along line 10—10, Fig. 1.

Fig. 11 is a sectional view taken along line 11—11, Fig. 2.

Mailing machines of the character to which my envelope moistening device is adaptable are typically illustrated in my U. S. Letters Patent No. 1,629,130. In mailing machines of this general type the envelopes are advanced through the machine by suitable conveying means, as is well known in the art, therefore, a detailed showing and description of the mailing machine proper is thought unnecessary.

The moistener feed rolls

As illustrated in the drawings, the machine frame 10 has rotatably supported therein a shaft 11 which is driven by suitable mechanism (not shown) associated with the conveyor of the machine. This shaft 11 has secured thereon the lower spaced apart feed rollers 12, 13, which form a part of the envelope conveyor. The innermost roller 12 is preferably provided with a substantially conical portion 12a adjacent its narrow contact face for a purpose hereinafter described.

The upper feed rollers 14, 15 are secured to a hollow shaft 16a which is rotatably mounted on a shaft 16 secured in a suitable yielding bracket 17 pivotally supported by the machine frame, and thus the upper rollers 14, 15 engage their coating rollers 12, 13 under pressure. The inner roller 14 is of a narrow face construction and engages with the narrow face of the lower roller 12, while the upper roller 14 is preferably provided with a face of greater width than its lower coating roller 13. While not strictly essential, I prefer to position the axis of my upper feed rollers 14, 15 slightly in advance of vertical alignment with the axis of the lower feed rollers 12, 13 so that the envelope in passing between these rollers will be deflected slightly downward from its normal travel line. The opposed feed rollers 12, 14 are each of an increased diameter relative to the opposed pair of feed rollers 13, 15. The two shafts 11, 16 are spaced parallel to one another at a distance substantially equal to a total of one-half of the diameter of each of the rollers 13, 15. With this construction, it is obvious that the distance between the centers of the shafts 11, 16 is less than the total of one-half of the diameter of each of the increased diameter rollers 12, 14.

To compensate for this variance of the increased diameters of the rollers 12, 14, and at the same time maintain the aforementioned center distance between the shafts, the roller 12 in this instance is formed of a resilient material

having an annular rim 12b, the face of which contacts with the face of its coating roller 14, and in this manner permits utilizing a set of rollers 12, 14 having an increased diameter relative to a set of opposed coating rollers 13, 15 mounted on parallel shafts 11, 16.

It is apparent that the rollers 12, 13, 14 and 15 will be rotated at the same R. P. M. and, therefore, the increased diameter rollers 12, 14 will have a correspondingly increased peripheral speed relative to the peripheral speed of the opposed coating rollers 13, 15.

As the envelope A is conveyed from the magazine or hopper (not shown) the flap edge of the envelope is guided against the travel line guide 18a. The envelope is carried by a suitable conveyor into engagement with the coating feed rollers 12, 13, 14 and 15. The inner coating rollers 13, 14 will engage only a narrow edge of the flap portion of the envelope and the conical portion will permit opening of the disengaged flap portion and will guide the same above the rotating shaft 11. The opposed edge portion of the envelope is engaged between the lower driven roller 13 and its coating roller 15, thus the intermediate body portion of the envelope and flap are unsupported while being advanced, by these feed rollers, into engagement with the moistener. As the envelope is advanced by these rollers, the increased peripheral travel of the rollers 12, 14 will urge the flap edge of the envelope to advance at a faster rate than the opposed envelope edge which is engaged between the rollers 13, 15. This action will cause the rear end of the envelope to be urged substantially toward the travel line guide 10a and the flap of the envelope thus advanced will not be displaced as aforementioned.

The envelope moistener

In this instance my moistener comprises a recessed body portion 20 which is provided with a tight-fitting cover 21 thereby forming a chamber 20a within the moistener body 20. The moistener body 20 has secured thereto a depending bracket 22 adapted to engage opposed pivot pins 23a of the moistener supporting bracket 23. This moistener bracket 22 is angularly adjustable about the pivots 23a by means of an adjusting screw 24 threadedly engaged in the U-shaped projecting arm 23b of the bracket 23 and a lock screw 25 threadedly engaged in the depending bracket 22. This permits adjusting the moistening face 20b relative to a horizontal plane. In its preferred position the inner end of the moistening face is disposed at an angle of substantially 2° to the horizontal plane. This will cause any tendency of fluid drip to take place at the inner end of the slot where suitable provision can be made for catching and disposing of the drips.

Preferably the moistening face 20b is of an arcuate contour and in this instance is provided with a central longitudinal capillary slot 20c communicating with the chamber 20a. While I have illustrated a single longitudinal slot 20c, it is obvious that the same results may be obtained by utilizing a plurality of capillary openings of any desired shape and such that fluid will not flow normally therefrom when the fluid supply container or chamber is air-locked.

The fluid supply

Fluid is supplied to the chamber 20a from an air-locked reservoir 26 which has a discharge conduit 27 engaging and supported in the bore

of a packing member 28, said conduit being open at its terminating end and also provided with a side opening 27a. This packing member 28, in turn, is engaged and supported in a chamber 20d, adjacent the moistening chamber 20a, and has a side opening 28a communicating with the chamber 20a and with which the conduit opening 27a is adapted for registration. Said chamber 20d is provided with an adjustable breather valve 10 which is disposed below the lower open end of the reservoir conduit 27.

The breather valve comprises a threaded bore 20e having a restricted valve seat opening 20f communicating with the chamber 20d. A valve stem 29 threadedly engages in the bore 20e and is provided, at its inner end, with a needle point 29a which is adapted to engage with the valve seat opening 20f. Also, the valve stem is provided with an enlarged head 29b and lever 29c to facilitate rotating the valve stem.

A compression spring 30 encircles the valve stem 29 and has its end bearings against the valve housing and inner side of the valve stem head 29b. This compression spring acts as a friction element and retains the valve stem 29 in an adjusted position.

Air channels 20g are provided at the opposed sides of the valve stem bore to permit air to communicate directly with the needle valve 29a 30 and its coacting valve seat opening 20f.

When the moistening device is in use, the needle valve 29a is opened to permit air to enter into the air-locked reservoir in a sufficient amount to break the air-lock and replenish the moistening fluid chamber 20a as its supply is reduced from discharge through the capillary slot 20c.

When the moistening device is not in use, the needle valve is closed, thereby air-locking the fluid supply and thus preventing discharge of the fluid through the capillary opening 20c.

The fluid supply reservoir

My fluid supply reservoir 26 is provided with a novel means for closing the communicating opening 28a between the reservoir 26 and moistening chamber 20a and which permits replenishing the reservoir without removing the same or without the necessity for using the usual additional shut-off valves.

To replenish the reservoir 26, the breather valve is closed and the reservoir body is simply rotated until the reservoir conduit opening 27a is in a non-registering position relative to the chamber 55 communicating opening 28a. This permits removing the air-locking closure or filler plug 26a and replenishing the reservoir without releasing or disturbing the air-locked body of fluid contained in the moistening chamber 20a. After 60 replenishment, the plug 26a is replaced and the reservoir is again rotated until the communicating openings 27a, 28a are in a registering position. When the air breather valve 28 is again opened, the moistening element is ready for continued operation.

Envelope flap presser rolls

To ensure positive contact of the separated envelope flap with the moistener opening 20c I have provided, in this instance, a plurality of impervious presser rolls 33, having circumferentially grooved faces, formed of a material lacking an affinity for moisture, such as for example, hard, smooth rubber or a non-corrosive metallic 70 finish. These presser rolls 33 are rotatably

mounted on a stationary shaft 34 which is secured to depending lugs 20h of the moistener 20. The shaft bearing bore of each of the presser rolls 33 is of a greater diameter than the shaft 34 upon which they are mounted.

Each roll is provided with a yielding contact ball 35 which is contained in a suitable aperture 36 and projects above the shaft 34 which is positioned in alignment with the moistener opening 20c. These balls 35 are forced outwardly, against the roll bores, by means of compression springs 37. In rotating, the roll bores have a point of contact against the balls 35 and a portion of the under peripheral face of the shaft 34.

This roll mounting permits each roll to act independently of one another in a forced yielding engagement with the moistening slot 20c. At Fig. 9 I have shown some of the rolls 33 in a depressed position as would be occasioned by an envelope and flap of unusual or varying thickness when passed between the rolls 33 and the moistening opening 20c.

Envelope guide and flap edge deflector

As previously stated, mailing machines to which my moistening device may be adapted, are generally used for sealing the envelope flaps, together with other required mailing operations such as printing the usual indicia; or optionally used for printing the indicia without sealing the envelope flap.

When the envelope flaps are to be sealed, I have provided an adjustable deflector shoe 40 which is normally urged downward, by means of a pull spring 40c, into the engaging path of an advancing envelope. This deflector shoe 40 is pivoted at 40a to a supporting plate 41 positioned adjacent the travel line of the envelope and spaced apart from the frame 10.

A control lever 42 threadedly engages an eccentric stud 43 which projects through an enlarged opening 41a, in the plate 41, to engage with the top inner face of an opening 40b in the deflector shoe 40. By means of said eccentric stud 43, the engaging face of the shoe may be adjustably positioned relative to the plane of the envelope guide plate 44 which is secured to the moistener. The guide plate 44 is disposed parallel to the plane of, and preferably elevated slightly above, the travel line of the envelope. This plate is provided with a forward edge 44c which is angularly disposed relative to the advancing edge of the envelope.

This guide plate 44 is provided with an advanced turned down portion 44a and angular engaging and separating edges 44b, 44c. With a guide plate so constructed and arranged, the advancing edge of the envelope will engage the turned-down portion 44a and elevate the body portion of the envelope for a purpose hereinafter set forth.

The control lever 42 is provided, at its upper end, with an operating and lock stud 42a which projects through a cam slot 41b in the plate 41. This cam slot 41b is formed so that the lever 42 may be actuated to control the operative and inoperative positioning of the deflector shoe 40, the lever being retained in either of its opposed positions by means of a pull spring 42b.

Secured in the lower end of the lever 42 is a guide stud 42e which projects through a suitable opening 41c. This guide stud 42e is positioned relative to the envelope guide plate 44 for a purpose hereinafter described.

Operation of the moistening device

When the device is to be used for moistening envelope flaps to be sealed, the control lever 42 is positioned as shown at Figs. 3, 5 and 6. This lever 42, in turn, positions the deflector shoe 40 in its operative position and the guide stud 45 in its inoperative position.

As the envelope A is advanced, as aforesaid, by the feed rolls 12, 13, 14 and 15, the envelope body is engaged by the forward turned-down edge 44a of the guide plate 44 and is carried up over said guide plate 44. As heretofore mentioned, the opposed feed rolls 12, 14 engage only a narrow flap edge portion of the envelope which leaves the envelope flap and central body portion of the envelope unsupported. As the advancing flap edge of the envelope engages the shoe 40, this edge is deflected below the plane of the envelope body which is now supported on the guide plate 44. This deflecting of the flap edge, together with the aforementioned elevating of the advancing edge, causes what may be conveniently termed a transversely extending buckle or bend in the advancing envelope body, see Figs. 5 and 6, and thus assures separation of the flap Ab from the envelope body and thereby, in a positive manner, assuring entrance of the angular edges 44b, 44c, of the guide plate 44, between said envelope body and flap.

By providing my guide plate 44 with angular engaging edges 44b, 44c in connection with my deflector shoe 40, I have found that envelopes having flaps of various contours or corner cuts Ac may be readily separated without employing additional devices or adjustments. It is obvious, and to be understood, that in utilizing my device with various widths of envelopes the moistening unit is adjustable toward and away from the flap edge travel line of the mailing machine frame so as to permit of the moisture being applied to the gummed area of the various envelope flaps.

The separated advancing envelope flap is engaged between the top face of the presser rolls 33 and the face 20b of the moistener, and while being advanced, the gummed area of the flap will draw sufficient moisture from the capillary opening 20c, due to the affinity of this gummed area for moisture, to completely moisten this said gummed area for subsequent sealing of the flap to the envelope body. In this instance, after the envelope flap has been moistened, the envelope is further advanced by coating feed rolls 45, 46 for further desired disposition.

When the mailing machine, with which my moistening device may be associated, is to be used for performing mailing operations without the sealing of the envelope flaps, the control lever 42 is moved to its raised position as shown at Fig. 5. This movement of the control lever, 50 through the stud 43, moves the deflector shoe 40 to its inoperative position and the guide stud 42e to its operative position in alignment with the plane of the guide plate 44.

When the guide stud 42e is in this operative position the flap edge and flap of the envelope will be guided above the separating edges 44b, 44c, and over the plate 44 and, therefore, the gummed area of the envelope flap is not permitted to engage with the moistening opening 20c of the moistener.

Thus, in a convenient manner, the mailing machine may be readily changed for sealing or non-sealing of the envelope flaps.

Having thus described my invention, it is obvious that modifications may be made therein

without departing from the spirit and scope of this disclosure, but what I claim is:

1. A moistening device for envelope sealing machines having a moistening arm with an air-locked fluid chamber and a fluid outlet passage of restricted size such that fluid will not flow normally therefrom when said chamber is air-locked, with means for engaging an envelope flap with said outlet passage to draw fluid therefrom; in combination with a second chamber adjacent said first chamber and having an opening communicating therewith with means for obstructing said communicating opening, an adjustable air breather valve communicating with said second chamber and an air-locked fluid supply communicating with said second chamber. 15

2. A moistening device for envelope sealing machines having a moistening arm with an air-locked fluid chamber and a fluid outlet passage of restricted size such that fluid will not flow normally therefrom when said chamber is air-locked, with means for engaging an envelope flap with said outlet passage to draw fluid therefrom; in combination with a second chamber adjacent said first chamber and having an opening communicating therewith, an air-locked fluid supply having a conduit rotatable in said chamber and adapted for registering and non-registering engagement with said communicating opening and an adjustable air breather valve for said fluid supply. 20

3. A moistening device for envelope sealing machines having a moistening arm with an air-locked fluid chamber and a fluid outlet passage of restricted size such that fluid will not flow normally therefrom when said chamber is air-locked, with means for engaging an envelope flap with said outlet passage to draw fluid therefrom; in combination with a second chamber communicating with said first chamber, a rotatable air-locked fluid supply reservoir engaging with said second chamber and adapted, through rotation of said reservoir, to interrupt the communication between said chambers, an adjustable air breather valve associated with said fluid supply. 35

4. A moistening device for envelope sealing machines having a moistening arm with an air-locked fluid chamber and a fluid outlet passage of restricted size such that fluid will not flow normally therefrom when said chamber is air-locked, with means for engaging an envelope flap with said outlet passage to draw fluid therefrom; in combination with a fluid supply tank for supplying fluid to said chamber with a closure whereby said tank may be air-locked above the level of the fluid in said tank with means forming a part of said tank whereby said chamber may be air-locked independent of said tank air-lock and an adjustable air breather valve associated with said fluid supply. 40

5. A moistening device for envelope sealing machines having a moistening arm with an air-locked fluid chamber and a fluid outlet passage of restricted size such that fluid will not flow normally therefrom when said chamber is air-locked, with means engaging an envelope flap with said outlet passage to draw fluid therefrom; in combination with a juxtaposed fluid supply tank for supplying fluid to said chamber with a closure whereby said tank may be replenished in its normal position and air-locked above the level of the fluid in said tank, together with means whereby said chamber may be air-locked independent of said tank air-lock and an ad- 55

- justable air breather valve associated with said fluid supply.
6. An envelope sealing machine having a moistening device, feeding means for advancing an envelope into engagement with said device to moisten the flap thereof, said feeding means including opposed sets of coacting feed rollers mounted on parallel shafts, one of said sets of rollers being of a larger diameter than its opposed set of rollers.
7. An envelope sealing machine having feeding means for advancing an envelope, said feeding means including opposed sets of coacting feed rollers mounted on opposed parallel shafts, one of said sets of rollers being of a larger diameter than its opposed set of rollers.
8. An envelope sealing machine having feeding means for advancing an envelope, said feeding means including parallel shafts with means for rotating said shafts at substantially the same speed, opposed pairs of coacting rollers mounted on said shafts, one of said pairs of coacting rollers being of a larger diameter than the other pair of rollers, one of said larger diameter rollers having a resilient annular area.
9. An envelope sealing machine having feeding means for advancing an envelope in contact with a travel guide, said feeding means including a pair of parallel shafts with means for rotating said shafts at substantially the same speed, opposed pairs of rollers mounted for rotation relative to said shafts and adapted to engage opposed parallel edge areas of said envelope, said rollers being further adapted to advance one edge of said parallel edges of said envelope at a greater rate of speed than the other parallel edge.
10. An envelope sealing machine having a moistening device with feeding means for advancing an envelope into engagement with said device, said feeding means including opposed pairs of coacting feed rollers mounted on parallel shafts, one of said pairs of rollers being of a larger diameter than the other rollers and one of said larger diameter rollers being adapted to yield under pressure of its said other larger diameter coacting roller.
11. An envelope sealing machine having a moistening device with feeding means for advancing an envelope into engagement with said device to moisten the flap thereof, said feeding means including opposed coacting rollers disposed in advance of said device, the axes of the upper and lower of said rollers being out of vertical alignment with one another.
12. An envelope sealing machine having a moistening device with feeding means for advancing an envelope into engagement with said device to moisten the flap thereof, said feeding
- means including coacting feed rollers disposed in advance of said moistening device, the bight of said rollers being positioned so as to direct the advancing envelope body and flap downwardly from its normal travel plane with an angular guide member adapted to engage said downwardly advancing envelope body and elevate said body with the flap thereof separated therefrom as said envelope is advanced.
13. A moistening device for envelope sealing machines having a moistening arm to deliver moisture to an advancing flap of an envelope and coacting feed rollers disposed relative to said arm for advancing the envelope; said rollers being adapted to engage a limited plane of the opposed edge faces of said envelope in a manner to permit the envelope flap to depend from the envelope body with guide means associated with one of said rollers, together with means for engaging said depending flap with said moistening arm.
14. A moistening device for envelope sealing machines having a normal air-locked fluid supply, a moistening arm, a fluid chamber in said arm and having a fluid outlet passage for delivering moisture to an envelope flap when said flap is engaged therewith, said passage being of restricted size such that fluid will not flow normally therefrom, a yielding rotatable element disposed relative to said passage and so arranged that an envelope flap to be moistened, when passed between said elements and across the mouth of said passage, will be pressed close thereto and operate to draw fluid therefrom against the influence of the air-lock of the fluid supply.
15. A moistening device as set forth in claim 14 wherein said rotatable element comprises a plurality of independently yieldable members.
16. A moistening device for envelope sealing machines having a moistening arm with a fluid outlet passage of a restricted size such that fluid will not normally flow therefrom for delivering moisture to an envelope flap when said flap is pressed close thereto; a shaft disposed relative to said arm and outlet passage, a plurality of rollers mounted on said shaft, the shaft-bearing bore of each of said rollers being of a greater diameter than said shaft with yielding elements, carried by said shaft, in engagement with the bores of said rollers and whereby a portion of the peripheries of said bores are yieldingly retained in an independent spaced relation to the periphery of said shaft and the outer periphery of said rollers normally in engagement with said arm.
17. A moistening device as set forth in claim 16 wherein said rollers are provided with interrupted peripheral faces.

FREDERICK W. STORCK.
